ELECTRICAL CONNECTOR

Raymond A. Swan, St. Ann, Mo., assignor to Joy Manufacturing Company, Pittsburgh, Pa., a corporation of Pennsylvania

Application May 23, 1957, Serial No. 46,320

Term of patent 14 years

(Cl. D26—1)

Fig. 2.

Fig. 1 is a perspective view of an electrical connector, showing my new design.

Fig. 2 is an end elevational view thereof.

The dominant features of my design reside in the portions shown in full lines.

I claim:

The ornamental design for an electrical connector, as shown and described.
